TENSION CONTROL FOR THE LET-OFF
MECHANISMS OF LOOMS

George W. Kretzschmar, Ridgewood, N. J.

Application August 26, 1950, Serial No. 181,663

3 Claims. (Cl. 139—97)

1

This invention relates to a visible and balanced tension control device for the let-off mechanisms of looms and the like, especially let-off mechanisms of the positive type.

During weaving operations, the warp is subjected to a longitudinal stress or tension by the take-up mechanism which acts progressively to take up the cloth as it is woven and such tension is subjected to a variation by the shed formation and beat-up of the reed. As the weaving proceeds, the diameter of the warp on the beam gradually diminishes and the rotative movement of the beam is increased as the warp becomes smaller in diameter. However, the tension is held constant or uniform for any diameter of warp and throughout the run thereof by a tension roller mounted in a tension unit between the whip roller and the warp beam because the resultant formed by the parallelogram of forces remains constant. The active or operating tension has long been determined from experience and varies with the type of warp and cloth construction.

When the loom is at rest, the warp and cloth either stretch or shrink due to varying atmospheric conditions as well as the construction of the weave. With the warp stretches while the loom is at rest, the tension on the threads decreases, and when the warp has shrunk the tension increases so that the tension becomes less or greater than the active or operating tension. When a loom is started from a position at rest and the warp has stretched, usually a light mark appears in the weave. When the warp has shrunk on a loom at rest and the loom is started, usually a dark mark appears in the weave. The light and dark marks are called starting marks.

The beat-up or the impact of the reed is obtained through momentum, that is the impetus due to the motion of the lay stroke and is relatively weak on the starting stroke or first pick. In practice, the weaver is instructed to manually open the lay structure fully on a loom at rest before standing the loom. However, this is seldom done with the result that the first beat up of the reed is weaker than when the loom is in operation. Spring or tight reeds also produce light or heavy impacts. All of which are factors varying the force of the impact of the first pick.

It is an object of the instant invention to provide a visible gauge reading of the warp and cloth tension at all times, whether the loom is in motion or at rest.

A further object is to provide looms with compensating means by which the tension on a ma-

2

chine at rest can be readily increased or decreased and returned to the operating tension before the loom is started.

Another object is to provide means by which tension can readily be increased over or decreased under operating or active tension to compensate for weaker impact or beat-up of the reed against the weave when the cloth and warp have stretched or to compensate for stronger impact of reed against reed when the cloth and warp have shrunk when the loom is at rest or after a pick-out of filling threads on a loom at rest.

Still another object is to provide at all times a balanced or equalized tension, that is equal pressure on both sides of the tension unit.

It is also an object of the instant invention to provide means for eliminating and preventing starting and joining marks, shirrs, barre, and all unevenness of weave.

An additional object is to provide a means on any loom for uniformity of weave.

Other objects of the instant invention will become apparent in the course of the following specification.

In the attainment of these objectives, a visible and balanced tension control device is provided. The device is constituted of an auxiliary cylinder or tube mounted on each side of the loom below and upwardly directed toward the free end of the pivotally mounted tension unit. On each auxiliary cylinder or tube is a plunger or piston and in operable engagement with each piston and the tension unit of the loom is a compression spring. A hollow master cylinder is interconnected with the auxiliary cylinders and in the cylinders so connected is a fluid. Mechanism is provided in the master cylinder for forcing the fluid into the auxiliary cylinders and to permit it to return to the master cylinder in order to vary the compression of the springs against the tension unit and in turn the tension in the warp threads passing over the rollers of the tension unit. A gauge connected with the fluid system gives a visible indication at all times of the magnitude of the tension of the warp threads and the weave while the tension control device provides a means for varying the tension.

The invention will appear more clearly when taken in conjunction with the accompanying drawing showing by way of example a preferred embodiment of the inventive idea.

In the drawing:

Figure 1 is a schematic longitudinal sectional view of the visible and balanced tension control

3

device constructed in accordance with the principles of this invention;

Figure 2 is a plan view of the control device shown in Figure 1; and Figure 3 is a schematic diagram of the parallelogram of forces showing the action of the tension unit.

Referring now in greater detail to the drawings where like reference numerals indicate like parts, reference numeral 10 indicates the tension unit, 11 the warp beam, 12 the take-up roller, 10 and 13 the visible and balanced tension control device.

The tension unit is constituted of the whip roller 14 and the tension roller 15 rotatably mounted by any known means between the end member 16 and a similar end member on the opposite side of the loom, the end members being pivotally mounted on the shaft 16a of the tension roller. The shaft 16a, in turn, is rotatably supported on opposite sides of the loom frame in a known manner. All pivots and gudgeons are mounted on ball bearings to obtain quick acting motion on all movable parts. When the warp travels over a tension roller and a whip roller to the take-up roller, the angle PAP', Fig. 3, formed by the whip roller with the take up and tension rollers for any diameter of warp beam remains constant. Thus, the resultant of the parallelogram of forces shown in Figure 3 remains constant, AP and AP' representing the force of the tension on the warp, and AR the resultant.

The visible and balanced tension control device 13 is constituted of a shelf 17 attached as desired to the warp stand or loom frame on opposite sides and adjacent the warp beam 11. Threaded through the bottom of each shelf 17 is a tubular member or tube or auxiliary cylinder 18 with open ends, one end protruding below the bottom and the other end extending upwardly or upwardly and forwardly in the direction of the whip roller 14. Reciprocable on tube or tubular member 18 is a plunger or piston 19, the upwardly directed end of which is closed as illustrated and substantially directed toward the shaft of the whip roller 14 or the free end of the end member. Adjacent the bottom of each piston is an integrally formed land 20. A spring 21 is placed around the outer surface of each piston between the land 20 and a downwardly directed arm 21a pivotally mounted on the end member of the tension unit adjacent the whip roller. Any suitable protuberance at the base of the arm 21a may be used to retain the spring member in position. Of course, the force of the springs could be directed against the shaft of the whip roller or even against the whip roller to accomplish the same end.

At the opposite end of the loom or in any other suitable location is a master cylinder 25 which may be formed with the hollow and internally threaded cylindrical member 26 with open ends, the bottom being closed by a base member 27 threaded over the open bottom. The open top of the cylindrical member 26 is internally threaded for the insertion of an externally threaded cylindrical head 28 actuated by any suitable handle member 29.

The tube or tubular member 18 and the cylindrical member 26 of the master cylinder are connected by a tube or pipe line 30, the tube to the auxiliary cylinder on the opposite side of the loom bifurcating from the tube 30 at the point 31.

A pressure fluid in the master and auxiliary cylinders and connecting tubes or pipe lines pro-

4

vides a means for varying the compression of the spring 21 of each auxiliary cylinder and in turn the force of the tension unit 10 against the warp threads.

In operation:

Suppose that the pressure gauge 32 connected into the tube 30 of the visible and balanced tension control device 13, under normal running conditions of the loom gives a reading of "M" pounds, and that the loom is closed down for a period of time. Variations in atmospheric conditions during the shutdown period may cause the warp threads to stretch to such an extent that when it is again desired to start the loom it is found that the reading on the gauge has fallen to "N" pounds. By threading the cylindrical head 28 of the master cylinder 25 into the cylinder 26 with the handle member 29, the liquid in the master cylinder will be forced out and through the tube or pipe line 30 to each auxiliary cylinder. Passing through the tubular member 18 of each auxiliary cylinder, the fluid will be forced into the pocket 33 between the tubular member and the piston until sufficient pressure has been built up to move the piston 19 outwardly toward the tension unit and with it the land 20 which compresses the spring 21 against the pivotally mounted arm 21a on each end of the tension unit. The increased compression of the springs 21 in turn forces the tension unit 10 to rotate clockwise about the pivotal point 16a and against the warp threads until the tension thereon is the same as that used in the normal operation or "M" pounds. On the other hand, if the warp threads shrink during the shut-down period and the tension on the warp threads has increased, the reverse of the previously described steps will restore the desired operating tension on the warp threads. During the normal running conditions, a glance at the gauge will quickly show any deviation of the tension from normal and the control device will provide a simple, ready, and inexpensive means for correcting the variation now chiefly guesswork and concerning which few persons ever agree. By using the two tension control units, one on each end of the tension unit, variations in tension on the warp threads caused by uneven warping and eccentricity of warp is likewise under control for the tension of the springs against the tension unit is the same on both sides of that unit irrespective of the inclination of the tension on unit relative to the horizontal. On a loom at rest or in motion the tension on the warp and cloth can readily be made greater or less than the operating or active tension thus compensating for variations in impact or beat-up of the reed against the weave. With the tension unit 10 providing a constant tension on the warp threads irrespective of the diameter of the warp beam 11, the variations in tension arising from the stretching and shrinking of the warp threads the wear of the machine and the variations of beat-up of the reed under control, it is possible to produce a cloth substantially free from defects and to eliminate waste.

While the mechanism described for varying the tension on the warp threads has been hydraulic, the same desirable results could be attained by using electrical, mechanical, electro-mechanical, or pneumatic means. Hence, it will be understood that the invention is not limited to the exact disclosure herein described but may lend itself to a variety of expressions within the scope of the appended claims.

What is claimed is:

1. In a loom having a frame of spaced side members, a warp beam rotatably mounted in one end of the frame, and a tension unit one end of which is pivotally mounted between the side members and above the warp beam; the improvements comprising a tension control device for the tension unit, the tension control device comprising an auxiliary cylinder disposed on each side member of the loom below the tension unit, the top of each auxiliary cylinder being open and upwardly directed toward the free end of the tension unit, a piston reciprocable on the outside of each auxiliary cylinder, the top of each piston being closed and in opposed relationship with the open top of the auxiliary cylinder, a spring member in operable engagement with each piston and the corresponding free end of the tension unit, means for simultaneously introducing a fluid pressure into each auxiliary cylinder and piston, and means for simultaneously releasing the fluid pressure from each auxiliary cylinder and piston.

2. A tension control device in combination with the tension unit of a loom, the loom having side members and the tension unit having a whip roller and a tension roller rotatably mounted between end members with the end members pivotally mounted about the tension roller journaled in the side members of the loom; the tension control device comprising an auxiliary cylinder disposed on each side member of the loom, the top of each auxiliary cylinder being open and upwardly directed toward the whip roller, a piston reciprocal on the outside of each auxiliary cylinder, the top of each piston being closed and in opposed relationship with the open top of the auxiliary cylinder, a spring member in operable engagement with each piston and the corresponding end member adjacent the whip roller, a pipe line interconnecting each auxiliary cylinder, a master cylinder coacting with the auxiliary cylinders, a second pipe line interconnecting the master cylinder with the first mentioned pipe line, a pressure fluid for the cylinders and interconnecting pipe lines, and means for varying the volume of the pressure fluid in the master cylinder.

3. A tension control device for the tension unit of a loom, the tension unit having a whip roller and a tension roller rotatably mounted between end members at the top of the loom adjacent the warp beam, and the end members being pivotally disposed about the tension roller with the whip roller inwardly directed therefrom; the tension control device comprising an auxiliary cylinder for each side of the loom, means for securing one end of each auxiliary cylinder to the side of the loom below the tension unit, the top of each auxiliary cylinder being open and upwardly directed toward the whip roller of the tension unit, a piston reciprocable on the outside of each cylinder, the top of each piston being closed and in opposed relationship with the open top of the auxiliary cylinder, each piston having an integrally formed land, a spring disposed intermediate the land and the corresponding end member adjacent the whip roller, a pipe line interconnecting the auxiliary cylinders in parallel, a master cylinder coacting with the auxiliary cylinder disposed on the loom, a second pipe line interconnecting the master cylinder with the first mentioned pipe line, a pressure fluid disposed in the cylinders and pipe lines, means for varying the fluid pressure comprising an open top on said master cylinder and an internally threaded opening formed in the open top, an externally threaded cylindrical head coacting with the internally threaded opening in the master cylinder, and a pressure fluid gauge disposed in one of the pipe lines.
